UNITED STATES PATENT OFFICE.

FRANK R. BUCK, OF PHILADELPHIA, PENNSYLVANIA.

DESIGN FOR A CARD-RECEIVER.

SPECIFICATION forming part of Design No. 13,268, dated August 22, 1882.

Application filed July 22, 1882. Term of patent 3½ years.

To all whom it may concern:

Be it known that I, FRANK R. BUCK, a citizen of the United States, residing at Philadelphia, in the county of Philadelphia and State of Pennsylvania, have invented a certain new and useful Design for Card-Receipters; and I do hereby declare the following to be a full, clear, and exact description of the invention, reference being had to the accompanying drawing, which forms part of this specification, in which the figure is a plan of my design.

The object of my invention is to produce a design which will permit card receivers and holders to be made of paper, card-board, paste-board, or other similar material which comes in flat sheets or lengths.

My invention consists of a card holder or receiver the design of which comprises a flat bottom, upturned sides, and scalloped corners.

Referring to the accompanying drawing, A is the bottom of the receiver, which is flat. B

| B B B are the sides, which are upturned and inclined from the perpendicular, and C C C are the corners, which are open or flaring and form scallops.

This design is graceful and symmetrical, and allows the device to be produced from a flat sheet of paper or similar material at slight expense and with but little labor.

What I claim is—

The design for a card-receiver herein described and shown, comprising a flat bottom, upturned inclined sides, and scalloped corners, substantially as and for the purpose set forth.

In testimony that I claim the foregoing I have hereunto set my hand this 21st day of July, 1882.

FRANK R. BUCK.
